CLAIM

The ornamental design for a package for DC-DC power converter or related circuitry, as shown and described.

DESCRIPTION

FIG. 1 is a perspective view of a package for a DC-DC power converter or related circuitry;

FIG. 2 is a bottom plan view thereof;

FIG. 3 is a side elevational view thereof, the opposite side being mirror image;

FIG. 4 is a top plan view thereof;

FIG. 5 is an end elevational view thereof;

FIG. 6 is another end elevational view thereof, this end being opposite the end of FIG. 5; and,

FIGS. 7 through 12 illustrate a second embodiment, where the descriptions of FIGS. 7 through 12 correspond to the descriptions of FIGS. 1 through 6, respectively.
